VANE STRUCTURE IN RECORD DISCHARGE
MECHANISMS

Francis John Offen, Swindon, England, assignor
to Garrard Engineering & Manufacturing
Company, Limited, Swindon, England, a cor-
poration of Great Britain

Original application May 7, 1941, Serial No.
392,200. Divided and this application August
27, 1942, Serial No. 456,441

6 Claims. (Cl. 274—10)

This invention relates generally to electrically operated sound reproducing machines and is more particularly directed to mechanism for supporting a plurality of records stacked above the turntable of a reproducing machine and operable in timed relation to other and cooperating mechanisms of the machine to successively release the records for disposition upon the turntable for reproduction.

The primary object of this invention is to provide an improved mechanism for machines for reproducing recordings on disc records, for effecting the delivery of such records of the same or different diameters, one at a time, for disposition upon the turntable or other support in reproducing position.

More specifically, this invention comprehends an automatically operating mechanism for electrically driven phonographs, for successively delivering a series of records stored in a stack formation above the turntable of a phonograph, for disposition thereon in reproducing position, by releasing the records one at a time from the bottom of the stack and concurrently lowering the remaining stacked records by one position to present another record in releasable position.

Other objects and advantages flowing from the practicing of my invention will become evident as the description proceeds.

For the purposes of this disclosure, I have elected to show and describe my invention as it may be incorporated in an electrically driven phonograph, such as shown in my co-pending application, Serial No. 392,200, filed May 7, 1941, which matured as Letters Patent No. 2,297,014, dated September 29, 1942, for Magazine phonographs, of which this application is a division, to cooperate in appropriately timed relation with other mechanisms thereof, in the functioning of the phonograph. However, this is merely illustrative, since, as will become manifest, my invention may be employed to equal advantage in other types of sound reproducing machines, electrically driven or otherwise, where automatic delivery of disc records to reproducing position is essential or desirable.

In the accompanying drawings, I have illustrated a preferred and practical embodiment of my invention, as used in a phonograph of the specific type disclosed in my aforesaid copending application, in which

Figure 1 is a view in perspective of an electrically driven phonograph embodying my invention.

Figure 2 is a side elevational view of the phon-

ograph shown in the preceding figure, disclosing the system of cams used to operate the various mechanisms, including that of the present invention.

5 Figure 3 is a view in perspective, with parts broken away, of the record magazine and associated vane shifting mechanism.

Figure 4 is a perspective view of a detail of Figure 3.

10 Figure 5 is a sectional view along the line 5—5 of Figure 3.

Figure 6 is a longitudinal section along the line 6—6 of Figure 5.

Figure 7 is a view in elevation, partly in section, showing the record magazine in readiness to discharge the lowermost record, and

15 Figure 8 is a view similar to Figure 7 showing the lowermost record discharged from the magazine for disposition upon the turntable.

20 Referring now to the drawings in detail, in which like characters of reference are employed to designate similar parts in the several views, the phonograph, as shown, includes a tone or pick-up arm 30 mounted on the motor board 32 and a turntable 33 embodying a record centering pin 34. A pair of diametrically oppositely disposed elevators 41 and 48 cooperate in the disposition of a record released from the magazine, generally indicated by the reference numeral 35, upon

25 30 the turntable, the records being retained in concentric relation in the magazine by the pin 37 vertically movable in the sleeve 38 carried by the arm 40. A knob 41 is provided for raising the pin 37 within its sleeve, to admit of stacking the records within the magazine 35. A record supporting arm 50 is rotatable into position beneath the record in the lowermost magazine position to cooperate therewith in supporting the stacked records, except during a period of coordination of

35 40 the phonograph mechanisms, when one of the elevators 41 coats with the magazine as a record support in engagement with a record is about to be released, as will be hereinafter explained in greater detail, another swingably mounted arm 42, being provided for reversing the records to admit of the reproduction of both recordings thereon, and conveying them to the storage receptacle 113 for disposition therein. For detecting the diameter of a magazine released record,

45 50 a feeler arm 51 carrying a roller 52 is mounted adjacent the turntable 33 while provision is made for automatically stopping the phonograph mechanisms by the actuation of a master switch, by means set in operation by the clockwise rotation of the arm 53 which abuts upon the edge

of the record in the lowermost magazine position to maintain the stop mechanism inoperative during the successive reproduction of the records delivered to the turntable from the magazine 35, the arm being free to rotate when the last record is released from the magazine and initiate the functioning of the stop mechanism to actuate the master switch which is manually actuatable by means of the knob 54.

The operating mechanism of the phonograph includes a system of cams shown in Figure 2, the shaft 60 carrying the gear 63 being driven through suitable reduction gearing from a motor by means of the pinion 62 in mesh with said gear 63, the other end of shaft 60 is provided with a gear 64 in mesh with pinion 65 to drive the stub shaft 66. The cams on the stub shaft operate pick-up arm 30 and the feeler arm 51, for example, while the cams on the sleeve 68, which is adapted to be coupled to the shaft 60 by the clutch 265, function in the operation of the record changing mechanism, one of these latter cams, indicated at 75, actuating the mechanism for releasing a record from the magazine, as hereinafter described.

The magazine 35 includes a series of vanes 36 rotatably mounted above the turntable 33, the records being released therefrom by the rotation of the lowermost vane clear of the edge of the record positioned thereon, the details of the vane actuating and control mechanism being clearly shown in Figures 3 to 6, in conjunction with Figure 1. The means for actuating and controlling the vanes is an improvement on the construction shown in U. S. Patent No. 2,188,769 to Downs.

The records R, which may be of mixed diameter, such as 10" and 12" records, are supported in vertically spaced relation by a series of vanes 36 forming the magazine adjacent one side of the motor-board 32, each vane being adapted to engage beneath the under marginal surface of a record to support the records in conjunction with the arm 30 in stacked position above the turntable 33. The support arm 50 is operated by one of the cams mounted on the cam sleeve 68 to cooperate with the actuation of the vanes in a manner to release the records one at a time onto the aforesaid elevators 47 and 48 which are then actuated to lower the record onto the turntable.

Before the lowermost record is released, elevator 47 is moved upward, lifting the stacked records from the support arm 50 which is then swung from beneath the lowermost record to clear the edge thereof. The lowermost record is then discharged from the magazine by the lateral rotation of the lowermost vane from beneath the record to permit the latter to drop onto the elevator 48 which has been raised to receive it, the arm 50 again swinging beneath the record in the lowermost magazine position, to support the stack, as the downward movement of the elevator 47 is initiated to coact with the like directional movement of the elevator 48 in conveying the record to the turntable. As each record is released from the magazine, the remaining vanes and the records engaged therewith are lowered a sufficient distance to bring the next vane, which becomes the lowest of the series, into position to be swung laterally for release of the record engaged therewith. See Figures 7 and 8.

The lateral movement of each vane in turn is effected in response to the rotation of the sleeve 74a and its segmental extension 74, by the cam 75 mounted on the sleeve 68 which is coupled to

the driving shaft 60 by the clutch 265, as aforesaid. As will be noted, the rotatable sleeve 74 embraces a column 76 on which the vanes are mounted for individual rotation independently of said column, the vanes as herein shown being assembled upon said column between the head 76a and the collar 76b, both of which are pinned to said column, with suitable spacers 76c interposed between adjacent vanes, to maintain them in vertically spaced relation. Obviously, in lieu of these spacers, each vane may embody an integral hub to attain the requisite spacing of the record-engaging portions thereof. The head 76a is chambered for the reception of a spring 76d, for maintaining the opposed surfaces of the vanes and cooperating spacers in close frictional association and to provide for the rotation of the series of vanes and said column as a unit, for returning the vanes to record-engaging position, when the column is vertically actuated in its bearings 76e, as hereinafter described.

The downward movement of the series of vanes, is produced in a like directional movement of the column 76, step by step, within its bearing 76e, the column being supported in its highest position, by the upper end of the segmental extension 74 of the sleeve 74a in engagement with the lowermost vane of the series. When the lowermost vane is rotated out of record-engaging position, as hereinafter described, to a storage position, column 76 moves downwardly until the next vane of the series is engaged with said extension to support the vanes in record-engaging position, and so on throughout the operation of the mechanism.

Each vane 36 is provided with a lateral projection 77 at its column engaging end, which is formed for abutting engagement with the face of the ledge 78 projecting laterally from the upper end of said segmental extension 74, which, in effect, is a continuation of the sloping cam surface 80, which rises from a point just above said ledge to its peak at the opposite side of said extension. Thus, when sleeve 74a and its segmental extension 74 are rotated as a unit, in a clockwise direction, the vertical surface of the ledge pressing against the engaged projection 77 of the lowermost vane 36 urges the vane in a like directional movement out of record-engaging position to a storage position at an angle of 90 degrees thereto. In this clockwise rotative movement of the segmental extension 74, the cam surface 80 thereof rides beneath the projection 77 of the next lowest vane 36 to support the remaining vanes of the series, the peak of the cam surface taking the load, when the ledge 78 reaches its ultimate position in the propulsion of the vane engaged thereby to its storage position. As the rotation of the segmental extension is reversed, in response to the spring actuation of the lever 85, the recession of the cam surface 80 beneath the vane projection abutting thereon produces a controlled downward movement of the record-supporting vanes with the column 76, until this movement is arrested as the projection 77 of the vane in engagement with the cam surface drops onto the ledge 78, as the segmental extension reaches its limit of counterclockwise movement. All of the vanes in record-engaging position are thus lowered by one position. To counteract any shock or noise which may result from the dropping of the projection 77 of the lowermost vane into position upon the ledge 78, the latter may embody a suitable buffer (not shown) of resilient material.

To prevent rotative movement of the vanes

above that in engagement with the ledge 78 of the segmental extension of the sleeve 74a, from record-engaging position, I provide a pillar 81 vertically mounted adjacent the vanes, which, as herein shown, is of a channel formation, the flange in juxtaposition to the column 76 being cut away to form a series of open end slots 82. Normally, the projections 77 of the vanes above the lowermost one in engagement with said ledge abut upon the portions of the flange between said open end slots to retain the vanes in record-engaging position.

The sleeve 74a, as stated is automatically rotated by the cam 75, the pinion 83 rigid with the lower end of said sleeve meshing with the rack 84 which is connected to one end of the lever 85 for reciprocation thereby. The lever 85 is pivotally mounted intermediate its ends, as at 86, the lower end thereof being connected to a fixed surface by the biasing spring 87. An arm 85a integral with said lever 85 carries a cam follower 88 continuously disposed in the path of rotation of the nose 15a of said cam 75 for engagement thereby to rock said lever 85 counterclockwise, to actuate the rack 84 to the left (Fig. 3), causing sleeve 74a and its segmental extension 74 to rotate in a clockwise direction to effect the rotation of the lowermost vane through an arc of 90° from its record-engaging position to its storage position, as set forth. The rack 84 is oppositely actuated (to the right) as the lever 85 is rotated clockwise under the influence of said spring 87, inducing counterclockwise movement of the sleeves 74a and its segmental extension 74 for the disposition of the projection 77 of the cam surface supported vane upon the ledge 78 of said extension, as heretofore explained.

When all of the records have been reproduced, the vanes which have been each rotated to storage position in the successive release of the records from the magazine, may be returned to record-engaging position by raising the column 76 by means of the knob 90 to a position where their respective projections 77 are aligned with the slots 82 in the pillar 81. The manual rotation of the column counterclockwise permits the vane projections to pass through said slots to abut upon the flange surfaces therebetween as the column is released to move downwardly to its initial position, with the lowermost vane projection bearing upon the ledge 78, as described. This insures correct alignment of all of the vanes for loading.

The lower end of the column 76 carries a ratchet wheel 91 rigid therewith which is engaged by a pawl 92 urged into engagement with said wheel by the spring 93, the pawl being pivoted to plate 94. This plate 94 is bifurcated, as at 95, to embrace the rod 96 for sliding movement thereon when column 76 is vertically actuated, the pawl 92 in engagement with the ratchet wheel 91 preventing rotation of the column 76 by the clockwise manipulation of the knob 90, as the plate 94 is restrained from rotation in engagement with said rod 96.

While I have described my invention more or less specifically with reference to the embodiment herein shown, as incorporated in a sound reproducing machine of a particular design, it will be obvious that my mechanism may comprise similarly functioning elements of other forms and may cooperate with phonograph operating mechanisms of different types to which it may be correlated for properly timed operation by suitable cam or other actuating means. All of such

changes in details of structure and arrangement of the elements of my mechanism being contemplated within the spirit and scope of this disclosure of my invention.

5 I claim:

1. Mechanism for delivering a series of records arranged in a stack in succession to the turntable of a phonograph, comprising a vertically movable column, a plurality of record-engaging vanes mounted on said column for individual rotative movement thereon, independently of said column, each vane embodying an angularly disposed projection at its column-engaging end, means mounted on said column for maintaining said vanes in vertically spaced relation, a sleeve surrounding said column, said sleeve including a segmental extension embodying a sloping cam surface at its upper end and a ledge having an upstanding wall and a lateral projection forming a depressed continuation of said cam surface at its lowest point, the lateral projection of said ledge being normally disposed for engagement by the projection of the lowermost vane in record-engaging position to support all of said vanes, the upstanding wall of said ledge being normally disposed for abutment by the projection of the lowermost vane in record-engaging position and means for oscillating said sleeve about said column, said means being operative upon movement in one direction to displace the lowermost vane engaged with said extension ledge out of record-engaging position and dispose the peak of said cam surface in supporting engagement with the projection of the next lowermost vane, said means upon movement in the opposite direction releasing the displaced vane from engagement with said extension ledge and permitting the lowering of all of the remaining vanes in record-engaging position, by gravity under the supporting guidance of said cam surface, for ultimate disposition of the projection of the succeeding lowermost vane in record-engaging position with said ledge.

2. Mechanism for delivering a series of records arranged in a stack in succession to the turntable of a phonograph, comprising a vertically movable column, a plurality of record-engaging vanes mounted on said column for individual rotative movement thereon, independently of said column, each vane embodying an angularly disposed projection at its column-engaging end, means mounted on said column for maintaining said vanes in vertically spaced relation, a sleeve surrounding said column, said sleeve including a segmental extension embodying a sloping cam surface at its upper end and a ledge having an upstanding wall and a lateral projection forming a depressed continuation of said cam surface at its lowest point, the lateral projection of said ledge being normally disposed for engagement by the projection of the lowermost vane in record-engaging position to support all of said vanes, the upstanding wall of said ledge being normally disposed for abutment by the projection of the lowermost vane in record-engaging position means for oscillating said sleeve about said column, said means being operative upon movement in one direction to displace the lowermost vane engaged with said extension ledge out of record-engaging position and dispose the peak of said cam surface in supporting engagement with the projection of the next lowermost vane, said means upon movement in the opposite direction releasing the displaced vane from engagement with said extension ledge and permit-

ting the lowering of all of the remaining vanes in record-engaging position, by gravity under the supporting guidance of said cam surface, for ultimate disposition of the projection of the succeeding lowermost vane in record-engaging position in engagements with said ledge, and fixed means engageable by the projections on the vanes above the vane in lowermost record-engaging position, to restrain said vanes against lateral displacement, in response to the actuation of the lowermost vane from its record-engaging position.

3. Mechanism for delivering a series of disc records in succession to the turntable of a phonograph, including a series of record-engaging vanes, means for supporting said vanes in vertically spaced relation for individual rotation in a horizontal plane, said means including a vertically movable element and a device oscillatable relatively to said element embodying a downwardly sloping cam surface terminating in a ledge having an upstanding wall and a lateral projection below the lowermost level of the cam surface, the lateral projection of said ledge being normally disposed to supportingly engage the lowermost vane of the series to maintain all of said vanes in record-engaging position, the upstanding wall of said ledge being normally disposed for abutment by the projection of the lowermost vane in record-engaging position, means for actuating said oscillatable device, said means being operable upon movement in one direction to displace said device to effect the lateral displacement of the vane in engagement with the ledge from record-engaging position and concurrently transfer the support of the vanes remaining in record-engaging position to said cam surface, the operation of said actuating means upon movement in the opposite direction permitting a downward movement of all of the vanes in record-engaging position, by gravity in response to the lateral displacement of said device, whereby the succeeding lowermost vane is guided in supported engagement with said cam surface downwardly toward said ledge for final disposition thereon in the termination of the opposite directional movement of said device.

4. Mechanism for successively delivering a series of records stacked above the turntable of a phonograph for disposition upon the turntable for reproduction, including a series of record-engaging vanes, a vertically movable and laterally rotatable element for supporting said vanes in vertically spaced relation for individual rotation relatively thereto in a horizontal plane, said vanes being conjointly movable vertically and rotatably as a unit with said element, a device mounted for oscillation relatively to said element embodying a downwardly sloping cam surface terminating in a laterally disposed ledge having an upstanding wall and a lateral projection below the lowermost level of the cam surface, the lateral projection of said ledge being normally disposed to supportingly engage the lowermost vane of the series to maintain all of said vanes in record-engaging position, the upstanding wall of said ledge being normally disposed for abutment by the projection of the lowermost vane in record-engaging position, means for actuating said oscillatable device, operable upon movement in one direction to displace said device to effect the lateral displacement of the vane in engagement with the ledge from record-engaging position and concurrently transfer the support of the vanes remaining in record-engaging position

10 to said cam surface, said latter means upon movement in the reverse direction permitting a downward movement of all of the vanes in record-engaging position, in response to the displacement of said device, whereby the lowermost vane is guided in supported engagement with said cam surface downwardly under gravity toward said ledge for final disposition thereon, in the termination of the latter oppositely directed movement of said device, and means for manually lifting said vertically movable element when all of the vanes of said series have been rotated out of record-engaging position, to restore said vanes to record-engaging position in a rotative movement of said element while raised.

5. Mechanism for successively delivering a series of records stacked above the turntable of a phonograph for disposition upon the turntable for reproduction, including a series of record-engaging vanes, a vertically movable and laterally rotatable element for supporting said vanes in vertically spaced relation for individual rotation relatively thereto in a horizontal plane, said vanes being conjointly movable vertically and rotatably as a unit with said element, a device mounted for oscillation relatively to said element embodying a downwardly sloping cam surface terminating in a laterally disposed ledge having an upstanding wall and a lateral projection below the lowermost level of the cam surface, the lateral projection of said ledge being normally disposed to supportingly engage the lowermost vane of the series to maintain all of said vanes in record-engaging position, the upstanding wall of said ledge being normally disposed for abutment by the projection of the lowermost vane in record-engaging position, fixed means in juxtaposition to said vanes, engageable by the vanes above the ledge engaging vane, for maintaining the vanes above the lowermost vane non-rotatable in record-engaging position, means for actuating said oscillatable device, upon movement in one direction to displace said device to permit the lateral displacement of the vane in engagement with the ledge from record-engaging position and concurrently transfer the support of the vanes remaining in record-engaging position to said cam surface, said latter means upon movement in the reverse direction effecting a downward movement of all of the vanes in record-engaging position, in response to the displacement of said device, whereby the succeeding lowermost vane is guided in supported engagement with said cam surface downwardly under gravity toward said ledge for disposition thereon, in the termination of the reverse directional movement of said device and means for manually lifting said vertically movable element when all of the vanes of the series have been rotated out of record-engaging position to return all of the vanes to record-engaging position, in a rotative movement of said element while raised.

6. In combination with an electrically operated phonograph having a turntable and mechanism for delivering disc records to said turntable for reproduction, said mechanism including a record magazine located above the turntable for supporting a series of records in stacked formation, an arm swingable into and out of position beneath the lowermost record in said magazine for cooperating with said magazine in supporting the stacked records, the records being releasable one at a time from the magazine from the bottom of the stack, an elevator adapted to alternate with said arm in supporting the records pre-

liminary to the release of the lowermost record from the magazine, a second elevator conjointly movable with the first elevator for disposing a record released from the magazine upon the turntable, said arm reassuming the support of the records when the released record is received by said second elevator; and means for effecting the successive release of the records from the magazine, said means including a vertically movable column, a plurality of record-engaging vanes mounted on said column for individual lateral rotation in a horizontal plane, independently of said column, each vane embodying an angularly disposed projection at its column engaging end, means mounted on said column for maintaining said vanes in vertically spaced relation, an oscillatable sleeve surrounding said column, said sleeve including a segmental extension embodying a downwardly sloping cam surface at its upper end, a ledge having an upstanding wall and a lateral projection forming a depressed continuation of said cam surface at its lowest point, the lateral projection of said ledge being normally disposed for engagement by the projection on the lowermost vane in record-engaging position to support all of said vanes, the upstanding wall of said ledge being normally disposed for

abutment by the projection of the lowermost vane in record-engaging position, mechanism for oscillating said sleeve about said column, said mechanism being operable upon movement in one direction to rotate the lowermost vane engaged with said extension ledge out of record-engaging position for the transfer of a record therefrom to the turntable, the rotation of said sleeve concurrently disposing the peak of said cam surface in supporting engagement with the projection of the next lowermost vane, said mechanism upon movement in the reverse direction being operable to rotate said sleeve for permitting a downward movement of all of the vanes in record-engaging position, under gravity induced by the like directional movement of the succeeding lowermost vane in record-engaging position in engagement with said cam surface for final disposition upon said extension ledge in the termination of the reverse directional movement of said sleeve, and fixed means adjacent said magazine formed for engagement by the projections of the vane above the ledge-engaging vane, for maintaining said vanes non-rotatable when in record-engaging position.

FRANCIS JOHN OFFEN.
